United States Patent Office

Des. 185,781
Patented Aug. 4, 1959

185,781

COLLAR

Erwin B. Jackman, New York, N.Y.

Application February 4, 1957, Serial No. 44,751

Term of patent 14 years

(Cl. D2—8)

FIG. 1

FIG. 2

Fig. 1 is a top plan view of a collar showing my new design, both faces thereof being identical in appearance; and

Fig. 2 is a front perspective view thereof as it appears in wearing position.

I claim:

The ornamental design for a collar, substantially as shown and described.
